UNITED STATES PATENT OFFICE.

GEORGE B. RENN, OF LOS ANGELES, CALIFORNIA.

SPRINKLING-HOSE HOLDER.

1,385,472.

Specification of Letters Patent. Patented July 26, 1921.

Application filed October 5, 1920. Serial No. 414,759.

To all whom it may concern:

Be it known that I, GEORGE B. RENN, a citizen of the United States, residing at Los Angeles, county of Los Angeles, and State 5 of California, have invented a new and useful Sprinkling-Hose Holder, of which the following is a specification.

This invention relates to devices for holding and supporting a water or sprinkling 10 hose for irrigating and similar purposes.

One of the objects of this invention is to provide a device of strong but still light construction adapted to withstand the vibrations of such a sprinkling hose without 15 losing its given position.

Another object is to provide a device so constructed as to allow an adjustment for discharging from a hose in many directions without changing the central position of the 20 device.

Another object is to provide means for easily engaging a water hose or similar devices which may just as easily be disengaged.

Other objects will appear from the following description and appended claim as well as from the accompanying drawing, in which—

Figure 1 is a side elevation of the device, to a certain extent arranged as a perspective view.

Fig. 2 is a detail end elevation of the clamping member of the device.

A standard 3 is preferably provided to allow the use of a sliding member or sleeve 35 4 for vertical adjustment. The standard 3 is preferably provided with prongs 5 or other similar means for allowing a pricking of the device into the ground on which the device is being used.

40 A rather large area can be covered with a device of this construction or design. The strong support of the prongs or feet supports a long and high standard without having to fear that the device may tip over, so 45 that the clamping member of the device may safely be moved up to a high position when desiring to throw or discharge the water over a long distance. In the manner the prongs or legs 5 are provided, they also 50 form a good support even if not pricked into the ground, as on sidewalks and other similar places.

The sleeve 4 is provided with a side arm or stem 6 for supporting the clamping member of the device. A set screw 7 serves to hold the sleeve in a desired position on the

standard. The clamping member proper is provided with a sleeve portion 8 to fit on the stem 6. The set screw 9 serves to properly hold the sleeve 8 of the clamping member on the stem 6. The two clamping jaws 10 are pivotally disposed on the pin end 11 of the clamping member. Handle members 12 project in the opposite direction from the pivot support in relation to the clamping jaws 10. Small bosses 13 are provided on the inside of the handle members for supporting and engaging a spring 14.

The spring naturally keeps the clamping member in normal clamping position and 70 condition, with the jaw members closely engaging over a water-hose or nozzle if so applied. The spring 14 presses the handle members 12 apart and thereby brings the jaw-members toward one another holding 75 the jaw members so normally in closed clamping position, as will easily be understood.

A water-hose can easily be held between the jaw-members 10 and remain so tightly 80 engaged while the set screw can be used for swinging the clamping member on its sleeve portion 8 to bring such a water-hose to an inclined position or even vertical position. In the drawing, the clamping member is so 85 illustrated as to bring a water-hose to a practically horizontal position when disposed between the jaw-members. The knob of the set screw 9 is illustrated rather large and almost in the way of anything passing 90 through the space between the jaw-members, but it will easily be understood that the knob may be smaller or the set screw 9 may be applied at another angle in relation to the pivot pin 11 of the clamping-member 95 so as to free the passage through the jaw members entirely without material change of the principle of the clamping member. The clamping member can then easily be set while a water hose is disposed between the 100 jaw members. The set screw 7 can always easily be set without interference to the clamping jaw-members, thus, the device can easily be adjusted to direct water in any direction while the water hose remains 105 firmly engaged within the device.

Having thus described my invention, I claim:

In a sprinkling-hose holder, a standard, a sliding member shiftable and turnable on 110 the standard, a stem on the sliding member normally projecting radially from the

standard, a sleeve member shiftable and turnable on the stem of the sliding member having a pin projecting sidewise from the sleeve forming the pivot pin for clamping members, clamping jaws engaging with the pin of the sleeve member, handles provided on the clamping jaws projecting beyond the pivot support, and a spring disposed between the handles so as to normally press 10 the handles apart for holding the clamping

jaws in a normally closed and clamping position.

In testimony that I claim the foregoing as my invention I have signed my name in the presence of two subscribing witnesses. 15

GEORGE B. RENN.

Witnesses:

OTTO H. KRUEGER,
JESSIE A. MANOCK.
